CLAIM

The ornamental design for a putting game, as shown and described.

DESCRIPTION

FIG. 1 is a front view of the putting game showing my new design;

FIG. 2 is a rear view of the putting game;

FIG. 3 is a right side view of the putting game;

FIG. 4 is a left side view of the putting game;

FIG. 5 is a top view of the putting game;

FIG. 6 is a bottom view of the putting game; and,

FIG. 7 is a top front side perspective view of the putting game in an environment of use.

The broken lines showing a golf club and golf ball in FIG. 7 are for the purpose of illustrating environmental subject matter that forms no part of the claimed design. The stippling in the drawings illustrates shading and not a surface pattern.
